PORTABLE CHARCOAL LIGHTING FIRE BOX

Edward M. Grandinetti, 2815 Los Flores Blvd.,
Lynwood, Calif.

Filed Sept. 4, 1963, Ser. No. 76,468

Term of patent 7 years

(Cl. D81—10)

FIG. 4.

FIG. 5.

FIGURE 1 is a side elevational view of a portable charcoal lighting fire box showing my new design.

FIGURE 2 is a top plan view thereof;

FIGURE 3 is a bottom view thereof;

FIGURE 4 is a rear view thereof; and

FIGURE 5 is a front view thereof.

The side opposite that shown in FIGURE 1 is a mirror image thereof.

I claim:

The ornamental design for a portable charcoal lighting fire box, substantially as shown and described.
